WILLIAM F. GEHRIG, OF NEWARK, NEW JERSEY, ASSIGNOR TO JOSEPH A. DAINTY,
OF NEWARK, NEW JERSEY.

REPEATING CAP-PISTOL.

1,041,267.

Specification of Letters Patent. Patented Oct. 15, 1912.

Application filed December 30, 1911. Serial No. 668,613.

To all whom it may concern:

Be it known that I, WILLIAM F. GEHRIG, a citizen of the United States, residing at Newark, in the county of Essex and State 5 of New Jersey, have invented certain Improvements in Repeating Cap-Pistols, of which the following is a specification.

The objects of this invention are to secure a pistol of the repeating type which 10 can be easily and conveniently loaded with a fresh roll of caps; to secure a construction in which this is done by "breaking" the pistol; to secure a positive feeding finger which is automatically removed entirely from the 15 cap-strip on its return stroke; to provide means for throwing said feeding finger into positive engagement with the cap-strip again; to enable said means, the feeding finger and the hammer, to be operated by a single spring; to prevent back-firing of the 20 pistol; to secure a simple construction which can be stamped out of sheet-metal, and to obtain other advantages and results as may be brought out in the following description.

Referring to the accompanying drawings, in which like numerals of reference indicate the same parts throughout the several figures, Figure 1 is a side elevation of the pistol with the hammer down and parts in 30 normal position, the near side-piece being removed; Fig. 2 is a view of the pistol from the reverse side, the near side-piece being removed and the barrel swung up into loading position. Fig. 3 is a view similar to Fig. 1, but showing the parts in their positions just previous to falling of the hammer when the trigger is pulled; Fig. 4 is a similar view immediately after the hammer has fallen and before the trigger has returned 35 to normal position; Fig. 5 is a similar view with the trigger almost back to normal position, and the feeding finger about to be reengaged with the cap-strip. Fig. 6 is a section of the pistol with the barrel in normal position, taken on line A—A of Fig. 2, looking in the direction indicated by the arrow; Fig. 7 is a perspective view of the anvil and slideway member detached; Fig. 8 is a perspective 40 view of the hammer detached; Fig. 9 is a perspective view of the trip detached; Fig. 10 is a perspective view of the trigger detached, and Fig. 11 is a perspective view of the feeding finger detached.

In the specific embodiment of the invention illustrated in said drawings, 1, 1 indicate the side pieces forming the casing of the stock of the pistol, and 2 indicates the barrel. At the rear end of the barrel is the magazine, comprising a top 3 with depending flanges 4, 5, adapted to enter the casing of the stock, between the said side pieces 1, 1, as shown, said magazine and the barrel being preferably formed of a single piece of sheet-metal. A hinge pin 6 extends through the pistol sides 1, 1 and the flanges 4, 5, near the rear end of the magazine, pivotally securing the magazine and barrel to the stock. By virtue of this feature, the barrel may be swung upwardly, as illustrated in Fig. 2, 70 to permit the insertion of a new roll 7 of caps between the flanges 4, 5. To receive said roll, preferably one flange, as 4, has stamped therefrom to stand perpendicular thereto, the pivot 8, and the other flange as 75 5 is cut away, as at 9, to permit the ready insertion of the roll of caps upon the pivot 8. Upon the hinge pin 6 is also mounted a member 10, which comprises a strip of sheet metal of a width approximately equal to the 80 distance between the side pieces 1, 1, said strip having ears 11, 11 bent forwardly and perforated to receive the hinge pin 6. From said ears downward the strip forms a slideway 12 for feeding the cap strip over, and it will be noted that the slideway is inclined 85 downwardly forward, as shown in Figs. 1, 3, 4 and 5, at an acute angle to the barrel. Above the ears 11, 11, the strip forms a vertical anvil 13, at substantially right angles 90 to the barrel, and at an obtuse angle to the slideway 12. Beyond said anvil 13 the strip is bent downward to the plane of the top 3 of the magazine, as at 14, and then extends 95 forward, as at 15, substantially in said plane and is rigidly connected to the magazine, as by tongues 16 grasping the rear edge of the top 3 both above and below the same. The member 10 is thus rigid with respect to the magazine and barrel, and swings therewith. 100 To hold the barrel down in normal position and prevent inadvertent swinging upward, the upper edges 17 of the side pieces 1, 1, which are substantially flush with the top 3 of the magazine, have at their forward ends inwardly bent lugs 18 which spring over the top 3 when the barrel is pressed down into normal position and hold the 105

same there. Strong enough pressure on the barrel 2 in swinging the same upward, will, however, disengage it from the said lugs 18, and swing it upward past the same.

5 To facilitate the assemblage of the various parts of the pistol, and hence to materially reduce the cost of manufacture, I mount the lock parts of the pistol upon a plate 19, which plate is constructed to conform to the interior profile of the butt of the pistol and is firmly held in such position when the side pieces 1, 1 are fastened together as will be hereinafter more fully explained. Secured to this plate 19 is the 10 pivot 20 upon which is mounted the trigger 21, and properly positioned therefrom and also secured to the plate 19 is another pivot 22 upon which is mounted the hammer 23. Other pivots or studs 24 and 25 are likewise 15 secured to the plate 19 to hold the requisite springs. One such spring 26 bears at one arm 27 against the stud 24, bows downward in its length to the trigger pivot 20, which pivot it encircles any convenient number of 20 times, and from which pivot the other arm 28 of the spring projects so as to engage the rear side of the trigger 21 and tend to retain the same in forward position against a shoulder 29 formed by the casing. The tension of this spring acts always to return the 25 trigger to the position illustrated in Fig. 1, when no external force, such as the application of the operator's finger, actuates the trigger otherwise in opposition thereto.

30 The hammer 23 is preferably made of sheet-metal and comprises a striking face 30 from which arms 31, 31 curve rearwardly downward in parallel relation to each other and are perforated near their extremities to 35 receive a pivot 22. Intermediate of said face 30 and the pivot 22, a trip 32 is hung between the arms 31, 31 of the hammer by means of pintles 33, 33, preferably projecting from the opposite edges of the strip of 40 sheet-metal from which said trip is preferably made. Said trip extends forwardly downward from the said pintles 33, as at 34, and is then bent at an acute angle to extend rearwardly, as at 35, beneath the pivot 22, 45 but still between the arms 31, 31. Ears 39 projecting from the edges of said bottom part 35 at the rear of the arms 31, 31 serve to limit forward swinging of the said trip 32. The other end of the trip or strip of 50 sheet-metal forming the same, extends rearwardly downward from the pintles 33, as at 36, and provides a seat for a spring 37 to hold the same against lateral displacement, as by prongs 38, 38. Said spring 37 lies in 55 the butt of the pistol, extending in front of the stud 24 and behind the stud 25, thus exerting a forward pressure at its upper end which engages the trip 32. One effect of such pressure is to rock the trip 32 upon its 60 pintles 33, 33 and throw the lower forward 65

part of the trip forward until its ears 39 engage the arms of the hammer, as shown in Fig. 1, for instance. Another effect or function of the said spring 37 is to swing the hammer forward with its striking face in 70 contact with the anvil.

The trigger 21 preferably comprises a piece of sheet metal folded so as to form a finger piece 40 rounded at its front side and hollow at its rear side to receive the arm 28 75 of the spring 26, said finger piece projecting from the casing of the pistol stock. At its upper end the side flanges 41, 41 of the trigger are perforated to receive the pivot 20, and furthermore said side flanges are extended rearward, as at 42, 42, to form the tripping arm of the trigger. This tripping arm extends rearward beneath the trip 32 of the hammer, when the parts are in normal position as shown in Fig. 1, and preferably 80 has thereat a feeding finger pivoted to itself and adapted to extend upward into engagement with a strip of caps upon the slideway 12. This feeding finger is shown as a piece of sheet-metal pivoted between said extensions 42, 42 by means of lateral pintles 43, 43, and normally engaged by the forwardly projecting point or angle of the trip 32, whereby said finger is pressed into positive engagement at its free end with the cap 85 strip. At its lower end or beneath the pintles 43, 43, the feeding finger preferably has a tail piece 44 which is curved rearwardly upward and forms an engaging surface projecting beyond the arms 42, 42. In this preferred construction, when the trigger is 90 pulled, said engaging surface of the tail piece 44 engages the angular shoulder of the trip 32 and swings the hammer rearward away from the anvil, the feeding finger at 95 the same time pushing the cap strip upward to feed a cap onto the anvil.

At a position substantially as illustrated in Fig. 3, the trigger disengages and passes the trip 32 of the hammer and said hammer falls against the anvil under the pressure of spring 37, exploding the cap. The parts are then momentarily in the position shown in Fig. 4, but the spring 26 instantly returns the trigger to normal position when the finger-piece is released, drawing its tripping arm downward over the inclined face 34 of the trip, which trip swings rearwardly under the pressure, without disturbing the position of the hammer, until the tripping arm of the trigger passes the angular shoulder of this trip, when the parts are returned to original position as shown in Fig. 1. It should be noted that the contact of the angular shoulder of the trip with the tail-piece of the feeding finger in pulling the trigger, causes said finger to fall back into the position shown in Fig. 4 after the trip is passed, and gravity will ordinarily hold it in such rearwardly tipped position dur- 125 130

ing the downstroke caused by forward movement of the trigger until it is again engaged by the trip and forced forward against the cap strip. There is thus no drag 5 whatever of the feeding finger upon the cap strip during its retractive movement. Possibly if the pistol was fired with the barrel pointing downward, gravity would tip the feeding finger forward during its back- 10 stroke, but even this can be avoided by introducing a slight amount of friction at the pivoting of the feeding finger upon the trigger, so that it will stay in the position into which it is swung. It is an important 15 point of my invention that a feeding finger is provided which positively engages the cap strip to feed the same forward, and wholly disengages said cap strip upon its retractive stroke.

20 It is a further feature of the invention that the slideway 12 is at an angle to the anvil 13, so as to protect unexploded caps which are approaching the anvil. Any 25 sparks or fire from an exploding cap on the anvil will fly off in the plane of the anvil and hence not come in contact with the next adjacent unexploded caps of the strip which lie under the overhang of the slideway.

The side pieces 1, 1 which form the casting of the stock may be joined together in any suitable manner, but I have shown for purposes of illustration marginal lugs 45 on one of the side pieces adapted to project through slotted lugs 46 on the other and be 35 bent over. When the two side pieces 1, 1 are joined together, the pivots and studs 20, 22, 24 and 25 engage at their free ends the inner surface of the side piece opposite the one against which the plate 19 lies and thus 40 positively hold said plate in proper position.

It will be noted from an inspection of Fig. 2 that when the pistol is broken for loading or the barrel member sprung outward as shown, the cap strip slideway 12 leaves the feeding finger 47, so that the same would fall forwardly downward out of position if means were not provided for preventing it. I therefore provide at the lateral edges of the feeding finger, above the arms 42, 42 of the trigger, shoulders 48, 48 which engage said arm when the cap strip slideway 12 swings away from the feeding finger, and prevent said feeding finger from 50 falling so far out of position that the slideway will not automatically reengage it when the barrel member is closed back into position after loading. These shoulders may be formed in any suitable manner, but I have 55 shown the feeding finger for its portion above said shoulders as of the same width as its portion having the pintles 43, 43, whereby a wider bearing of the end of the feeding finger upon the cap strip is secured.

60 Various modifications can be made in the

actual structure and embodiment of my invention without departing from the spirit and scope of the invention, and I do not wish to be understood as limiting myself except as required by the following claims 70 when construed in view of the prior art.

Having thus described the invention, what I claim is:

1. In a pistol, the combination with an anvil and a slideway for a cap strip leading thereto, a hammer, a feeding finger adapted to propel a cap strip along said slideway, means for pressing said feed finger against the cap strip during its forward stroke and releasing it at the end of said forward stroke for the back 80 stroke, and a trigger to actuate said hammer and feeding finger.

2. In a pistol, the combination of an anvil and a slideway for a cap strip leading thereto, a feeding finger adapted to propel 85 a cap strip along said slideway, a hammer, a trip upon said hammer adapted to press said feed finger against the cap strip during its forward stroke and to release it at the end of said forward stroke for the back 90 stroke, and means for actuating said finger and hammer.

3. In a pistol, the combination with an anvil and a slideway for a cap strip leading thereto, a feeding finger adapted to propel 95 a cap strip along said slideway, a hammer, a trip pivoted upon said hammer adapted to press said feed finger against the cap strip on its forward stroke and to release it on the back stroke, and means for moving 100 said feed finger back and forth.

4. In a pistol, the combination of an anvil and a slideway for a cap strip leading thereto, a feeding finger adapted to propel a cap strip along said slideway, a hammer, 105 a trip pivoted upon said hammer adapted to press said feed finger against the cap strip on its forward stroke, a spring for said trip, and a trigger adapted to move said feeding finger back and forth and to engage said trip on the back stroke.

5. In a pistol, the combination of an anvil and a slideway for a cap strip leading thereto, a hammer, a spring-projected trip on said hammer, a trigger, and a feeding finger 115 on said trigger adapted to engage said trip on its forward stroke, the trigger engaging said trip on the back stroke.

6. In a pistol, the combination of an anvil and a slideway for a cap strip leading thereto, a hammer, a trip on said hammer, a spring engaging said trip to project the same from the hammer and hold said hammer against the anvil, a trigger, and a feeding finger on said trigger adapted to propel 120 the cap strip along said slideway and to engage said trip when the trigger is pulled, and a spring adapted to return the trigger to normal position and press said trip out of 125 the way of said feed finger.

7. In a pistol, the combination of an anvil and a slideway for a cap strip leading downwardly forward therefrom, a hammer, a spring projected trip on said hammer, a feeding finger adapted to propel a cap strip along said slideway to engage said trip on its forward stroke and to fall away from said cap strip by gravity on its return stroke, and a trigger carrying said feed finger and adapted to engage the trip on said return stroke of the feed finger. 35
8. In a pistol, the combination of an anvil and a slideway for a cap strip leading thereto, a hammer, a trip pivoted on said hammer, a trigger, a finger pivoted on said trigger adapted to engage said trip and be forced thereby into engagement with a cap strip to propel the same along the slideway when the trigger is pulled, the passage of the finger pivot beyond a line between the trigger and hammer pivots causing the finger to disengage the said trip and release the hammer, a spring for the hammer, and means for returning the trigger to original 40 position and causing it to push the trip out of the way of the feed finger on its return stroke. 45
9. In a pistol, the combination with a stock, of a member pivoted to said stock and providing a barrel a magazine an anvil and a slideway for a cap strip leading to said anvil, means on the stock for propelling a cap along said slideway, a hammer and a trigger both on said stock, and means for holding the pivoted member in closed relation to the stock. 50
10. In a pistol, the combination with a stock, of a barrel member pivoted to said stock providing a magazine an anvil and a slideway for a cap strip leading to said anvil, a hammer and a feeding finger both mounted on said stock, means on the stock for actuating said hammer and feeding finger, and means for supporting said feeding finger when the pistol is broken for loading. 55
11. In a pistol, the combination of a casing, a barrel member pivoted to said casing and having a magazine and cap strip slideway normally lying in said casing, means on said casing releasably engaging the barrel member to hold it in closed position, an anvil, a hammer, a trip pivoted on said hammer, a spring engaging said trip to project the same and throw said hammer against the anvil, a feeding finger adapted to propel a cap strip forward upon said slideway, and simultaneously engage said trip on the hammer, and a trigger for actuating said finger, said trigger adapted to engage said trip on the back stroke of the finger and to support said finger when the barrel member is swung open for loading. 60
